UNITED STATES PATENT OFFICE.

THOMAS A. WATTS, OF SPRINGFIELD, OHIO, ASSIGNOR TO THE SPRINGFIELD METALLIC CASKET COMPANY, OF SPRINGFIELD, OHIO, A CORPORATION OF OHIO.

HANDLE FOR BURIAL-CASKETS.

1,326,382.

Specification of Letters Patent. Patented Dec. 30, 1919.

Application filed May 25, 1917. Serial No. 170,845.

To all whom it may concern:

Be it known that I, THOMAS A. WATTS, a citizen of the United States, residing at Springfield, in the county of Clark and State of Ohio, have invented certain new and useful Improvements in Handles for Burial-Caskets, of which the following is a specification.

This invention relates to improvements in handles, and more particularly to that class of handles which are especially adapted for use in connection with burial caskets.

The object of this invention is to provide a simple, economical and effective arrangement for pivotally connecting the handle arm to the ear.

In the accompanying drawings:—

Figure 1 is a rear view of the ear, handle and connecting arms.

Fig. 2 is a section on the line 2—2 of Fig. 1.

Fig. 3 is a section on the line 3—3 of Fig. 1.

In the said drawings, 1 represents a sheet metal ear of well known form, provided in the usual way with the openings 2 to receive the screws which fasten it to the casket. The ear also has the usual arm-receiving openings 3, the wall of the ear above the openings being bulged out as shown in Figs. 2 and 3 so that the upper and lower edges of each opening will be off-set with respect to each other. The handle 7 has secured thereto in a well-known way the handle arms, which are of the usual sheet metal construction having a top wall 5 and side walls 5^a.

My improvement consists in the manner of connecting these handle arms with the ear. The lower edge of each opening 3 has projecting therefrom a rearwardly-extending integrally formed lug 4 which is bent or curled about a pintle 6 the ends of which extend through openings in the rounded extensions 5^b which project from the lower edges of the side walls of the arms at the extreme inner end thereof. With the form

of ear shown in the drawing, the part 4 may be bent to shape before the pintle is inserted, but in the small type of ear where but a single opening 3 is employed, it is necessary to insert the pintle 6 through the apertures in the arm and then bend the part 4 about the pintle, this being due to the fact that with this type of ear there is not sufficient room to insert the pintle after the arm is in position to receive the same. In any event, the part 4 is caused to tightly embrace the pintle 6 so as to prevent displacement thereof, the pintle being immovable and the arms 55 swinging thereon.

In Figs. 2 and 3 the handle arm is shown in raised position, that is, in the position it would be in when the weight of the casket is on the handles. It will be noticed that the top wall of the handle bears against the upper edge of the opening 3 and that the extensions 5^b bear against the wall of the ear adjacent the lower edge of the opening 3 so that all strain is removed from the pintles.

Having thus described my invention, I claim:—

In a handle of the character described, a sheet metal ear having an opening, the upper and lower edges being offset with respect to each other, a lug formed integrally with said ear and extending rearwardly from the lower edge of said opening, a pin, said lug being bent about said pin to retain the same with the ends of the pin projecting beyond said lug, a sheet metal handle arm extending into said opening and having two perforated extensions to receive said pin, the arrangement being such that when said handle is under load the upper portion thereof will contact the upper edge of the opening and said extensions will contact the ear at the lower edge of said opening.

In testimony whereof, I have hereunto set my hand this 14th day of May, 1917.

THOMAS A. WATTS.

Witness:

CHAS. I. WELCH.
